UNITED STATES PATENT OFFICE.

CHARLES A. BRAUNGER, OF ELIZABETH, NEW JERSEY, ASSIGNOR OF ONE-HALF TO
JAMES HENRY PRUITT, OF CISSNA PARK, ILLINOIS.

MANUALLY-ACTUATED ACTION FOR FIREARMS.

Application filed July 15, 1921. Serial No. 485,057.

To all whom it may concern:

Be it known that I, CHARLES A. BRAUNGER, a citizen of the United States, and a resident of Elizabeth, in the county of Union 5 and State of New Jersey, have invented a new and Improved Manually-Actuated Action for Firearms, of which the following is a full, clear, and exact description.

This invention relates to manually actuated action primarily designed for use in firearms.

The object of this invention is to produce a manually actuated action of simple construction, having few parts, which gives 15 positive action.

This and other objects of the invention will be more clearly understood from the following detailed description and accompanying drawings.

20 Figure 1 is a cross section through a missile thrower showing the manually actuated action as applied to this device; and

Figure 2 is a cross section through the manually actuated action showing the hammer about to be released.

Referring to the above-mentioned drawings, a recoil tube 10 is slidable on the block 11 to which the hand grip casing 12 is connected. This recoil tube 10 is provided with 30 a slot 41 so that it may slide on the block

11. An opening 13 is provided in the block 11. A firing pin 14 having an enlarged head 15 extends through the opening 13 in the block 11 and through an opening 16 in 35 the projection 17 on the recoil tube 10 which is in alinement with the opening 13. These openings 13 and 16 serve as bearings for the firing pin 14. An opening 18, which is in alinement with the opening 13, serves as

40 a slideway for the head 15 of the firing pin 14. Mounted in the continuation of the opening 18 is a piston 19 which is controlled by a spring 20 that abuts against a cap 21 mounted on the recoil tube 10.

45 A trigger 22 which has an enlarged upper portion 23 is pivoted in the casing at 24. The trigger has the usual trigger guard 25 which is integral with the hand grip casing 12. Slidably mounted in an opening 26 in

50 the enlarged portion 23 of the trigger is a latch 27. Located in the opening 26 and co-operating with the latch 27 to normally hold it pushed outward is a spring 28. The head portion of the latch 27 has an arch-shaped face 29. A seat is cut in the en-

larged portion 23 of the trigger and upon this seat the head of the latch 27 slides and prevents binding of the latch as it slides back and forth in the opening 26.

A hammer 30 is pivoted in the casing 12 60 at 31. This hammer extends upward and fits in between the head 15 of the firing pin 14 and the piston 19 which slides in the extension of the opening 18. The upper end of this hammer is curved so that it will 65 slide on the piston 19 as it is drawn back during the cocking action. A projection 32 which is integral with the hammer normally engages with the curved face 29 of the latch 27. A projection 33 integral with 70 the hammer and extending downward is engaged by an arm 34 of a spring which is mounted on a projection 35 in the hand grip casing 12. This projection 33 has a curved face 36 on which the end of the arm 75 34 of the spring slides when the hammer is rotated about its pivot point 31. The arm 37 of the spring engages in a slot 38 cut in the portion 23 of the trigger. This arm 37 of the spring tends to rotate the finger portion 22 of the trigger forward and normally holds it in contact with the front wall 80 of the slot 39 in which it moves.

The operation of this device is as follows:

85 The finger portion 22 of the trigger is drawn backward, as shown in Figure 2, thus rotating the latch 27 about the pivot 24. As the latch 27 is in contact with the projection 32 of the hammer 30, the hammer is 90 rotated about the pivot point 31. This cocking action of the hammer 30 forces the piston 19 backward thus energizing the spring 20. The projection 32 slides along the face 29 of the latch 27 and finally when the cocking action is completed the projection 32 slides off the arc-shaped face 29 and the hammer is released. The springs 20 and 34 rotate the hammer forward, striking the firing pin 14 which was drawn backward 95 during the cocking action of the hammer. The latch 27 when it is released from the projection 32 is forced outward by the spring 28 and comes in contact with the arc-shaped face 40 of the hammer 30. When 100 the trigger is released it is rotated about the pivot point 24 by the arm 37 of the spring and the latch 27 slides along the face 40. Upon the trigger reaching its normal forward position the latch 27 is projected 105 110

downward and engages the projection 32. The parts are now in position for a repetition of the cocking and firing movements.

This action has been shown and described 5 in conjunction with a missile thrower but the action might be applied to a variety of firearms and other devices which are operated by a manually actuated action of this type. Many modifications might be made 10 in the shape of the different parts.

Claims:

1. In combination with a missile thrower including a firing pin, a manually actuated action comprising a spring-controlled pivoted trigger, a spring-controlled pivoted hammer, a spring-controlled reciprocating latch in conjunction with the trigger which holds the latter in engagement with the hammer during the cocking action and which 15 releases them on the completion of the said action, a spring having two arms, one co-operating with the hammer the other the trigger to return both to their normal positions, and an auxiliary spring to increase the 20 force of the firing motion of the hammer.

2. In firearms, a manually actuated action comprising a casing, a hammer and a trigger pivoted mounted in the casing, a spring secured to the casing and interposed between the trigger and hammer for retaining 25 them in their normal positions and ready for the cocking action, and a spring-controlled latch slidably mounted on the

trigger to move in the plane of movement of the trigger, said latch engaging the hammer during the cocking action and releasing it for the firing stroke.

3. A manually actuated action comprising a casing, a trigger pivotally mounted in the casing, a latch slidably mounted on the trigger to move in the plane of movement of the trigger, a hammer pivotally mounted in the casing, means for retaining the hammer and trigger in their normal positions ready for the cocking action, and means for projecting the latch into engagement with the hammer to associate the trigger and hammer during the cocking action, said latch being released from the hammer for the firing stroke.

4. In firearms, a manually actuated action comprising a casing, a trigger having a shoulder formed thereon pivotally mounted in the casing, a hammer having a projection formed thereon pivotally mounted in the casing, a latch slidably mounted on said trigger shoulder and movable in the plane of movement of the trigger for engaging the hammer projection to connect the two during the cocking action and serving to release the hammer for the firing stroke, and means for normally retaining the trigger and hammer in position ready for the cocking action.

CHARLES A. BRAUNGER.
